UNITED STATES PATENT OFFICE.

WALTER V. TURNER, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTROFLUID-PRESSURE BRAKE.

1,286,842.

Specification of Letters Patent.

Patented Dec. 3, 1918.

Application filed February 28, 1918. Serial No. 218,745.

To all whom it may concern:

Be it known that I, WALTER V. TURNER, a citizen of the United States, residing at Wilkinsburg, in the county of Allegheny and State of Pennsylvania, have invented new and useful Improvements in Electrofluid-Pressure Brakes, of which the following is a specification.

This invention relates to electro-fluid-pressure brakes, and the principal object of the invention is to reduce the number of train circuits required, by providing means for controlling both the application and the release of the brakes through common train circuits.

In the accompanying drawing, the single figure is a diagrammatic view, partly in section, of an electro-fluid pressure brake apparatus embodying my invention.

According to the construction shown in the drawing, a triple valve device 1 may be provided comprising a casing having a piston chamber 2 connected to the brake pipe 3 and containing piston 4, and having a valve chamber 5 connected to auxiliary reservoir 6 and containing a main slide valve 7 and an auxiliary valve 8 adapted to be operated by piston 4.

A release valve 9 controls communication from the brake cylinder 10 to exhaust port 11 and magnet 12 is provided for operating said valve. An application magnet 13 is adapted to operate a valve 14 for venting fluid from piston chamber 2 through passage 15 to a passage 16 leading to brake cylinder 10.

According to my invention, a polarized relay magnet device 17 is provided having an armature 18 carrying at one end contacts 19 and 20, and at the opposite end contacts 21 and 22.

Two train wires 23 and 24 are provided, one of which may be dispensed with if a ground return is employed, and the relay magnet 17 is connected in circuit across the train wires. The train wire 24 is connected to a contact 25 adapted to be engaged by contact 20 and train wire 23 is connected to contact 26 and adapted to be engaged by contact 22.

A contact 27 connected to wire 28 leading to one terminal of release magnet 12, is adapted to be engaged by contact 19, and contact 29, connected to wire 30 leading to

one terminal of application magnet 13, is adapted to be engaged by contact 21.

On the head car or locomotive, means are provided for reversing the direction of current flow in the train wires 23 and 24, and in operation, if it is desired to effect an application of the brakes electrically, current is caused to flow in a direction for energizing the relay magnet 17 so that the armature 18 will be thrown to the position shown in the drawing. In this position, the circuit is completed through the application magnet 13 from train wire 23 through magnet 13 to wire 30, through engaging contacts 29 and 21 to armature 18 and thence through engaging contacts 20 and 25 to train wire 24.

When application magnet 13 is energized, the valve 14 is opened to vent fluid from piston chamber 2 through passage 15 to passage 16 leading to brake cylinder 10, and the triple valve piston 4 is then actuated to shift the valves 7 and 8 in the usual manner, so as to supply fluid from the auxiliary reservoir 6 to the brake cylinder 10.

In order to hold the brakes applied, the direction of flow of current in the train wires 23 and 24 is reversed, so that the relay magnet is energized to shift the armature 18 to the position opposite that shown in the drawing, in which the circuit of the application magnet 13 is opened, while the circuit of the magnet 12 is closed by way of train wire 23 through magnet 12 to wire 28 and thence through engaged contacts 27 and 19 to armature 18 and through engaged contacts 22 and 26 to train wire 24.

The magnet 12 being thus energized, the valve 9 is operated to cut off passage 31 from exhaust port 11.

The application magnet being deenergized, the valve 14 will be closed, so as to cut off the further venting of fluid from piston chamber 2, and since the brake pipe 3 will be recharged from the head end of the train or the usual manner, the piston chamber 2 is also recharged, and the triple valve parts will be shifted to release position, in which brake cylinder passage 16 is connected by cavity 32 in valve 7 with passage 31. Since the release valve 9 is now closed, however, fluid cannot escape from the brake cylinder 10 and the brakes will therefore be held applied.

If it is desired to release the brakes, the flow of current is cut off from the train wires 23 and 24, so that the release magnet 12 is deenergized and the valve 9 opened to permit fluid in the brake cylinder to exhaust from passage 16 through cavity 32 to passage 31 and thence to exhaust port 11.

Having now described my invention, what I claim as new and desire to secure by Letters Patent, is:—

1. In an electro-fluid-pressure brake, the combination with an application magnet and a release magnet, of a train line for supplying current to both magnets and means operated by flow of current through the train line in one direction for connecting one magnet to the train line and by flow in the reverse direction for connecting the other magnet to said train line.
2. In an electro-fluid-pressure brake, the combination with an application magnet and a release magnet, of a train wire and means for connecting one or the other of said magnets to the train wire according to the direction of current flow through said train wire.
3. In an electro-fluid-pressure brake, the combination with a brake cylinder, an application magnet adapted upon energization to effect an application of the brakes, and a release magnet adapted upon energization to close the exhaust from the brake cylin-

der, of a train wire and means for connecting one or the other of said magnets to said train wire according to the direction of flow of current through the train wire.

4. In an electro-fluid-pressure brake, the combination with a magnet for controlling the application of the brakes and a magnet for controlling the release of the brakes, of a train wire and a polarized relay magnet device energized according to the direction of current flow through said train wire for connecting one or the other of said magnets to the train wire.

5. In an electro-fluid-pressure brake, the combination with a brake cylinder, a triple valve device for controlling the admission and release of fluid under pressure to and from the brake cylinder, a magnet valve device for venting fluid from the triple valve device to effect an application of the brakes, and a release valve device for controlling the exhaust of fluid from the brake cylinder, of a train wire and a polarized relay magnet device for connecting one magnet valve device to the train wire upon flow of current through the train wire in one direction and for connecting the other magnet valve device to the train wire upon flow of current in the reverse direction.

In testimony whereof, I hereunto set my hand.

WALTER V. TURNER.
